Palio, Leopold, Inc., New York

UNITED STATES PATENT OFFICE.

JOSEPH F. MORAN, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY CASE.

Application filed May 18, 1927. Serial No. 192,198.

This invention relates to certain improvements in vanity cases and particularly to improvements in an improved catch for use with these cases.

5 In certain types of vanity cases, which are small boxes having a body and a cover of light metal, employed for packaging toilet articles, such as powder and rouge compacts, the body and cover members are pivotally associated 10 on a hinge and provided with a catch for holding these parts in locked relation.

In certain of these boxes, a mirror is carried in the cover and a toilet preparation, as a compact, in the body, and one of these parts 15 is provided with a bead defining the edge of such parts, as for instance the body, the cover seating within this bead. Such a box is shown in United States Letters Patent No. 1,499,855, dated July 1, 1926, to Coryell, and the present 20 invention has for its especial object an improvement in the catch construction shown in this patent, by which there is provided a catch which will act to positively engage over the bead and hold the body and the cover of 25 the box securely together, this catch being formed integrally with the cover, or with a bezel in the cover which holds the mirror in place.

25 A further object of the invention is to produce a box of this type which shall have few 30 parts and in which the parts may be easily and quickly associated and which will be sufficiently strong and durable for the purpose contemplated.

35 With these and other objects not specifically referred to in view, the invention consists in certain novel parts, arrangements and combinations which will be described in connection with the accompanying drawings and the 40 novel features pointed out in the claims hereunto annexed.

In these drawings,—

Figure 1 is a face view of the improved box or case, the parts being shown closed;

45 Figure 2 is a similar view of a modified construction of box;

Figure 3 is a side view of the box;

Figure 4 is a plan view of one way of assembling the box and cover, and

50 Figure 5 is a face view of the modified catch shown in Figure 2.

Referring now to these drawings, the box selected to illustrate the invention comprises cover and body shell members 1, 2, which are 55 arranged, when in closed position, to meet in

a thin edge. The body member is provided with an annular bead 3, which defines the rim of the body member. The cover member 2 is provided with a downwardly extending flange 4 which, when the box is closed, engages 60 with the inner edge of the bead 3. The cover and body members are pivotally associated in any suitable manner.

Opposite the catch, the metal of the cover is turned to form a hinge knuckle 5 capaci- 65 tated to receive a pintle wire 6, shown in the form of a semi-circular wire, the ends of which are spaced apart from each other, as shown in Figure 4. In assembling the parts, the wire 6 is inserted in the body 2 and 70 fits under the bead 3, this bead being cut away at 7, as shown in Figures 1 and 2, to permit the hinge knuckle to fit therein. With this construction, the parts can be assembled with 75 great quickness. In the particular construc- 75 tion illustrated, there is a mirror 8 in the cover, the mirror being held in place in any suitable way, as by a ring or bezel 9. Opposite the hinge, the box is provided with a catch which is formed to engage around the bead 80 and positively hold the body and cover together. This catch may be formed and asso- 80 ciated with the box in various ways. Refer- 85 ring to Figures 1 and 3, the metal of the cover is formed with a projection 10, which is bent 85 or otherwise shaped to produce a groove 11 deep enough to receive and lap over the bead 3, the projection then being bent outwardly and upwardly to make a finger hold 12, by 90 which the cover may be separated from the body for use.

In Figures 2 and 5 is shown a modified form of construction. As here shown, the catch is formed integrally with the bezel or ring 9 which holds the mirror in place in the 95 cover 1. Where this construction is adopted, the flange 4 of the cover, opposite the hinge 5, is cut away as indicated at 13 in Figure 2 to permit the groove 11 to engage the bead 3.

While the invention has been shown and 100 described in its preferred form, it will be understood that certain variations in the shape of the box and bezel may be made without departing from the invention as defined in the appended claims.

105 What I claim is:

1. In a vanity case, the combination of body and cover members hinged together, a bead defining the rim of the body member and a flange on the cover member arranged 110

for frictional engagement within the bead, a toilet article in the cover, an annular member held by frictional engagement within the flange of the cover and acting to hold the 5 toilet article in position, a catch integral with the annular member and bent to form a groove arranged to engage over the bead and hold the cover and body in closed position and then bent to form a finger hold, extending out- 10 wardly from the head and a hinge knuckle uniting the body and cover opposite the catch.

2. In a vanity case, the combination of body and cover members hinged together, a bead defining the rim of the body member and a 15

flange on the cover member arranged for frictional engagement within the bead, a mirror in the cover, an annular member held by frictional engagement within the flange of the cover and acting to hold the mirror in po- 20 sition, a catch integral with the annular member bent to form a groove arranged to engage over the bead and hold the cover and body in closed position and then bent to form an out- 25 wardly extending finger catch, and a hinge knuckle uniting the body and cover opposite the catch.

In testimony whereof, I have hereunto set my hand.

JOSEPH F. MORAN.
